Francis M. Wright,
ATTORNEY.

UNITED STATES PATENT OFFICE.

WILLIAM F. HASKINS, OF SAN FRANCISCO, CALIFORNIA, ASSIGNOR TO MILTON BERNARD, OF ALAMEDA, CALIFORNIA.

BUILDING-BLOCK.

1,150,363.

Specification of Letters Patent. Patented Aug. 17, 1915.

Application filed April 20, 1915. Serial No. 22,584.

To all whom it may concern:

Be it known that I, WILLIAM F. HASKINS, a citizen of the United States, residing at San Francisco, in the county of San Francisco and State of California, have invented new and useful Improvements in Building-Blocks, of which the following is a specification.

The object of the present invention is to provide improved toy building blocks which can be assembled in a great variety of ways for building toy structures and which can be secured together without the use of nails, tacks, string or paste.

In the accompanying drawing, Figure 1 is a perspective view of one of my improved building blocks; Figs. 2, 3, 4 and 5 are similar views of other blocks of different forms; and Fig. 6 is a perspective view of a structure made by my improved building blocks.

Referring to the drawing, 1 indicates a toy building block formed of wood, and which, to distinguish it from other building blocks hereinafter described, I term a tie-bar, since it is generally, although not necessarily, used for horizontally disposed members of a structure. In form it is rectangular and comparatively thin, and varies in length, and has a mortise 2 in its edge extending entirely around it.

3 indicates a block of another style, which, because of its general use as a supporting member, I term a post-block. In cross-section it is of a general rectangular form, but from the center of each of the four sides 4 of the rectangular projects outwardly a tenon 6 of a thickness to fit snugly in the mortise 2 in the tie-bar 1, either at its sides or at its ends, a little pressure being required to force it into the mortise, so that, when forced in the tie-bar, it is supported upon the post-block by the friction between its flanged portions, extending beyond the mortise, and the sides of the tenon 6 of the post-block. The mortises at the ends of the tie-bar are each of depth such that a tenon of the post-block can be pressed into the mortise to its full depth and so that the edges of the flanges of the tie-bar abut against the sides 4 of said post-block.

7 indicates a block of a third style, which, to distinguish it from the others, I term a dowel-block. The dowel-block is simply a piece of wood of square cross-section and of

the same thickness as the tenons of the post-block. 55

The above-described blocks, of different sizes, constitute the main elements of a complete set of toy building blocks, as they co-operate with each other in a novel manner, but I also provide auxiliary blocks such as the plank block 8, shown in Fig. 4, which is in the form of an ordinary plank or board, and the finishing block 10 shown in Fig. 5, which is a rectangular block of wood with a wedge-shaped recess at one end, used for representing chimneys in toy building structures, or for other purposes, as may be found convenient. 60

In Fig. 6 is illustrated a bridge constructed of my improved building blocks. It will be seen that two post-blocks 3 are placed horizontally on the ground to represent supports for the bridge, and on these are erected post-blocks, to which are connected, in the manner above-described, ends of tie-bars, the other ends of said tie-bars being connected to other post-blocks. The post-blocks in the middle portion of the bridge are connected to each other by tie-bars and on three tie-bars in the middle of the bridge are supported dowel-blocks, which in turn support tie-bars narrower than the first-named, the ends of which are connected in the usual manner to post-blocks of greater or less 75 height. The upper ends of the latter are connected to one another and to the upper ends of the outermost post-blocks by tie-bars some of which are sloping. The post-blocks on opposite sides of the bridge are connected 80 in the usual manner to tie-bars which form supports for plank-blocks, constituting the roadway of the bridge. 85

The above is only one of many different ways in which the blocks can be used. 90

I claim:—

1. In combination with thin tie-bars, each having a mortise in its edge entirely around its periphery, post-blocks each rectangular in cross section and having projecting outwardly from the center of each of its sides a tenon, of the proper thickness to fit in the mortise of each tie-bar just sufficiently tight to firmly support either member upon the other by the friction between the co-engaging 100 parts. 105

2. In combination with thin tie-bars, each having a mortise in its edge entirely around

its periphery, post-blocks each rectangular in cross section and having projecting outwardly from the center of each of its sides a tenon, of the proper thickness to fit in the mortise of each tie-bar just sufficiently tight to firmly support either member upon the other by the friction between the co-engaging parts, and dowel-blocks each consisting of a piece of wood of square cross section

and of like thickness with the tenon of each 10 post-block.

In testimony whereof I have hereunto set my hand in the presence of two subscribing witnesses.

WILLIAM F. HASKINS.

Witnesses:

FRANCIS M. WRIGHT,
D. B. RICHARDS.
